end sleeve 35 fixed thereon by dimpling at 36, and thereby fixed with the thrust washer 33 on the spiral feed member 28. The rear end sleeve 35 is proportioned in diameter for a slip fit within the operating cap or sleeve 12 so as to provide for rotation of the spiral feed member 28 by turning the operating sleeve 12 with respect to the barrel 10. At its forward end the spiral feed member 28 is further fitted with a suitable bushing collar 37 or the like formed for bottoming rotatably at the previously mentioned annular tapered shoulder 18 adjacent the forward end of the barrel 10, the upper portion of bushing collar 37, in the arrangement illustrated in Fig. 2, being slotted to engage a rib at the lower end portion of spiral feed member 28 so as to key the feed member 28 and bushing 37 for rotation together.

The spiral feed member 28 is maintained in assembled relation within the barrel 10 for rotation from the operating sleeve 12 by means of a retaining element 38 fixed at the rear end of the longitudinally slotted guide tube 24 to bear forwardly at the rear face of the thrust washer 33; the rear end portion of the guide tube 24 being additionally slotted at 39 opposite the longitudinal slot therein to have the retaining element 38 disposed therethrough, and the guide tube 24 being crimped inwardly above the retaining element 38 to lock it in place. The retaining element 38 is formed as a pin member having a straight length disposed through the slotted rear end of the guide tube 24 and extending sufficiently at opposite sides of the guide tube 24 to overlie an adjacent portion of the rear face of thrust washer 33. The retaining element 38 may, if desired, be further formed with arcuate extensions 41 arranged for disposition within a recess formed at the rear face of the thrust washer 33 by a cylindrical boss 42, so as to provide for increased frictional contact between the retaining element 38 and the thrust washer 33 and thereby provide further resistance to inadvertent retracting motion of the feed mechanism under writing pressure.

In addition to the guide tube 24 and spiral feed member 28, the lead feed mechanism further comprises the previously mentioned clutch member 26 and propelling member 27. The propelling member 27 is formed with a rear nut portion 43 and a forward shank portion 44. The nut portion 43 is arranged in the guide tube 24 rearwardly of the clutch member 26 and has a lug portion 45 formed thereon to extend laterally through the longitudinal slot in the guide tube 24 and engage the threads 31 of the spiral feed member 28 for effecting longitudinal or axial sliding movement of the propelling member 27 within the guide tube 24 upon rotation of the feed member 28. The shank portion 44 of the propelling member 27 extends forwardly from the nut portion 43 for slidable disposition within the clutch member 26 and has the side thereof opposite the nut portion lug 45 notched so as to form a rearwardly facing shoulder 46 forwardly thereon and a rearwardly spaced forwardly facing shoulder 47; being advantageously angled so as to face outwardly as well as forwardly.

The clutch member 26 is in turn formed intermediate its length with ears 48 arranged for bottoming at the rearwardly facing shoulder 46 on the propelling member shank portion 44 and is further formed with a flexible arm portion 49 extending rearwardly of these ears 48 to the forwardly facing shoulder 47. Adjacent its rear end this flexible arm portion 49 has a boss 50 formed outwardly therein for normally riding the inner face of the guide tube 24 so as to maintain the flexible arm portion 49 disposed inwardly in abutment with the forwardly facing shoulder 47 and thereby fix the clutch member 26 on the propelling member 27 for movement therewith within the guide tube 24, as seen best in Fig. 2. Adjacent its forward end, however, the guide tube 24 has an aperture 51 aligned therein to receive the boss 50 and thereby allow outward shifting of the clutch member flexible arm portion 49 to release the propelling member

27 for sufficient separate axial movement adjacent the forward end of guide tube 24 to eject a spent lead from the clutch member 26, as illustrated in Fig. 7.

This separate movement of the propelling member 27 is initiated when rotation of the spiral feed member 28 has resulted in advancing the clutch member 26 in guide tube 24 to the point at which the boss 50 on the clutch member flexible arm portion 49 reaches the guide tube aperture 51 and is thereby released for shifting laterally outward. At the same time, the forward end of clutch member 26 bottoms in the intermediate bore 22 of writing tip 11 with a resulting reaction at the angled forwardly facing shoulder 47 of propelling member shank portion 44 that displaces the flexible arm portion 49 outwardly to release the propelling member 27 for further separate advancement upon continued rotation of the spiral feed member 28 until the propelling member nut portion 43 bottoms at the forward end of the feed member 28 with the shank portion 44 projecting slightly from the lead-size bore 23 at the forward end of writing tip 11.

After ejection of a spent lead from the clutch member 26 by such separate movement of the propelling member 27, reverse rotation of the spiral feed member 28 results in retracting propelling member 27 within guide tube 24 so as to bottom the clutch member ears 48 again at the rearwardly facing shoulder 46 on the propelling member shank portion 44 and thereby force the clutch member boss 50 from the guide tube aperture 51 causing it again to ride the inner face of the guide tube 24 and return the flexible arm portion 49 to abutting position at the forwardly facing shank portion shoulder 47 to restore the fixed disposition of the clutch member 26 on the propelling member 27 for movement therewith within the guide tube 24.

In connection with this retracting movement of the propelling member 27 in the guide tube 24 it should also be noted that the forward face of the thrust washer 33 is formed with a plurality of spaced radial lugs 52 surrounding the guide tube 24 within the central bore 29 of spiral feed member 28. These lugs 52 are arranged so that the front sides thereof facing in the direction in which the spiral feed member 28 is rotated for retracting the propelling member 27 lie in radial planes with respect to the axis of feed member 28, while the opposite or back sides thereof are slanted at about 45° from the extending lug edges. By this arrangement, the thrust washer lugs 52 are disposed for selective lateral abutment with the lugs 45 of the propelling member nut portion 43 so as to lock the spiral feed member 28 against rotation and thereby stop further rearward movement of the propelling member 27 before it can jam or wedge against the forward face of the thrust washer 33 upon reaching its fully retracted position within the guide tube 24 and propelling member 28.

As a result, the threads 31 of spiral feed member 28 are afforded positive protection against thrust damage from overtravel of propelling member 27 adjacent the rear end of guide tube 24. Without such protection, the feed member threads 31 may be subjected to severe thrust strain by the wedging action of the propelling member lug portion 45 between the forward face of thrust washer 33 and the rearmost feed member threads 31 if rotation of feed member 28 is continued after propelling member 27 has been fully retracted. The thrust strain resulting in this situation is directed to a principal extent axially of the feed member 28 so as to be exerted across the threads 31 in the direction most likely to damage them.

Thrust strain of this sort is particularly damaging when a plastic spiral feed member 28 of the type disclosed in the previously noted copending applications is employed, because this type of feed member 28 has substantial lengths of its threads 31, at the longitudinal grooves 30, that are unsupported laterally and that are accordingly

relatively weak against such a thrust strain so as to be broken rather easily if the propelling member 27 is made to overtravel carelessly at the rear end of the feed member 28. By forming the thrust washer 33 with the forward face lugs 52, however, any possibility of such overtravel is entirely eliminated.

A spaced plurality of the lugs 52 are provided on the thrust washer 33 so as to allow for varying registration therewith of the spiral feed threads 31, the spiral disposition of which in the body of the feed member 28 may be rotated differently in different feed members of the type disclosed in the above noted copending applications. Also, the back sides of the lugs 52 are slanted, as noted above, so that the propelling member lug portion 45 may slip past a first thrust washer lug 52 at which it does not abut sufficiently for seating adequately against the front face of a succeeding lug 52 without any danger of otherwise creating a thrust strain, such as is being provided against, by jamming at the extending edge of the first lug 52.

The present invention has been described in detail above for purposes of illustration only and is not intended to be limited to this description or otherwise except as defined in the appended claims.

I claim:

1. In a mechanical pencil, a guide tube, a clutch member and a propelling member slidably disposed in said guide tube, said propelling member comprising a shank portion extending forwardly for slidable disposition within said clutch member and having a rearwardly facing shoulder formed forwardly thereon and an angled shoulder formed rearwardly thereof facing forwardly and outwardly, said clutch member having ears formed thereon intermediate its length for bottoming at the rearwardly facing shoulder on said propelling member shank portion and having a flexible arm portion extending rearwardly of said ears to said angled shoulder, the inner face of said guide tube maintaining said flexible arm portion inwardly disposed in abutment with said angled shoulder and thereby fixing said clutch member on said propelling member shank portion for movement therewith within said guide tube except adjacent the guide tube forward end at which said guide tube is formed for allowing outward displacement of said flexible arm portion by said angled shoulder to release said propelling member for separate movement.

2. In a mechanical pencil, a longitudinally slotted guide tube, a clutch member and a propelling member slidably disposed in said guide tube, said propelling member comprising a rear nut portion having a lug thereon extending laterally through the longitudinal slot in said guide tube and a shank portion extending forwardly for slidable disposition within said clutch member, the side of said shank portion opposite said nut portion lug having a rearwardly facing shoulder formed forwardly thereon and an angled shoulder formed rearwardly thereof facing forwardly and outwardly, said clutch member having ears formed thereon intermediate its length for bottoming at the rearwardly facing shoulder on said propelling member shank portion and having a flexible arm portion extending rearwardly of said ears to said angled shoulder, said flexible arm portion being maintained inwardly disposed in abutment with said angled shoulder by the inner face of said guide tube to fix said clutch member on said propelling member shank portion for movement therewith within said guide tube except adjacent the guide tube forward end at which said guide tube is formed for allowing outward displacement of said flexible arm portion by said angled shoulder to release said propelling member for separate movement.

3. In a mechanical pencil, a longitudinally slotted guide tube, a clutch member slidably disposed within said guide tube and having the forward end thereof formed for gripping a lead, and a propelling member slidably dis-

posed in said guide tube and rearwardly of said clutch member, said propelling member comprising a rear nut portion having a lug thereon extending laterally through the longitudinal slot in said guide tube and a shank portion extending forwardly for slidable disposition within said clutch member, the side of said shank portion opposite said nut portion lug having a rearwardly facing shoulder formed forwardly thereon and an angled shoulder formed rearwardly thereof facing forwardly and outwardly, said clutch member having ears formed thereon intermediate its length for bottoming at the rearwardly facing shoulder on said propelling member shank portion and having a flexible arm portion extending rearwardly of said ears to said angled shoulder, said flexible arm portion having a boss formed outwardly therein adjacent its rear end and normally riding the inner face of said guide tube so as to maintain said arm portion disposed inwardly in abutment with said angled shoulder and thereby fix said clutch member on said propelling member shank portion for movement therewith within said guide tube, and said guide tube having an aperture adjacent its forward end aligned with the boss in said clutch member flexible arm portion for receiving said boss to allow outward shifting of said flexible arm portion so as to release said propelling member for sufficient separate movement adjacent said guide tube forward end to eject a spent lead from said clutch member.

4. In a mechanical pencil, a feed mechanism comprising a longitudinally slotted guide tube, a clutch member and a propelling member disposed for axial sliding movement in said guide tube, and a spiral feed member coaxially surrounding said guide tube and rotatable with respect to said guide tube about the common axis thereof, said propelling member being formed with a rear nut portion and a forward shank portion, said nut portion being arranged rearwardly of said clutch member and having a lug thereon extending laterally through the longitudinal slot in said guide tube and engaging said spiral feed member for effecting axial sliding movement of said propelling member within said guide tube upon rotation of said feed member, said shank portion extending forwardly for slidable disposition within said clutch member and having the side thereof opposite said nut portion lug notched to present spaced forwardly and rearwardly facing shoulders thereat, said clutch member having ears formed thereon for seating in said notch and bottoming at said rearwardly facing shoulder and having a flexible arm portion extending rearwardly of said ears to said forwardly facing shoulder, the inner face of said guide tube maintaining said flexible arm portion inwardly disposed in abutment with said forwardly facing shoulder and thereby fixing said clutch member on said propelling member shank portion for axial movement therewith within said guide tube except adjacent the guide tube forward end at which said guide tube is formed for allowing outward flexing of said clutch member flexible arm portion to release said propelling member for separate movement.

5. In a mechanical pencil, a longitudinally slotted guide tube fixed within said barrel adjacent its forward end, a spiral feed member surrounding said guide tube within said barrel and rotatably bottomed forwardly therein, a thrust washer fixed on the rear end of said feed member, means engaged by said guide tube adjacent its rear end and held thereby in forwardly bearing relation at the rear face of said thrust washer, a clutch member and a propelling member disposed for longitudinal sliding movement in said guide tube, said propelling member comprising a nut portion and a shank portion, said nut portion being arranged rearwardly of said clutch member and having a lug thereon extending laterally through the longitudinal slot in said guide tube and engaging said spiral feed member for effecting longitudinal sliding movement of said propelling member within said guide tube upon rotation of said feed member, said shank por-

tion extending forwardly for slidable disposition within said clutch member with the side thereof opposite said nut portion lug having a rearwardly facing shoulder formed forwardly thereon and an angled shoulder formed rearwardly thereof facing forwardly and outwardly, said clutch member having ears formed thereon intermediate its length for bottoming at the rearwardly facing shoulder on said propelling member shank portion and having a flexible arm portion extending rearwardly of said ears to said angled shoulder, said flexible arm portion being maintained inwardly disposed in abutment with said angled shoulder by the inner face of said guide tube to fix said clutch member on said propelling member shank portion for movement therewith within said guide tube except adjacent the guide tube forward end at which said guide tube is formed for allowing outward displacement of said flexible arm portion by said angled shoulder to release said propelling member for separate movement adjacent said guide tube forward end, and said thrust washer having a plurality of radial lugs formed at the forward face thereof about said guide tube for selective lateral abutment with said propelling member nut portion lug adjacent the rear end of said guide tube to stop movement of said propelling member therat.

6. In a mechanical pencil, a barrel, a longitudinally slotted guide tube fixed within said barrel adjacent its forward end and extending rearwardly and axially therein, a spiral feed member coaxially surrounding said guide tube within said barrel and rotatably bottomed forwardly therein, a thrust washer fixed on the rear end of said feed member, means engaged by said guide tube adjacent its rear end and held thereby in forwardly bearing relation at the rear face of said thrust washer, a clutch member slidably disposed within said guide tube and having the forward end thereof formed for gripping a lead, and a propelling member slidably disposed in said guide tube rearwardly of said clutch member and comprising a nut portion having a lug thereon extending laterally through the longitudinal slot in said guide tube and engaging said spiral feed member for effecting longitudinal sliding movement of said propelling member within said guide tube upon rotation of said feed member, said clutch member being confined by said guide tube for engaging said propelling member and moving therewith except adjacent the guide tube forward end at which said guide tube is formed to release the engagement of said clutch member with said propelling member and allow sufficient separate forward movement of said propelling member to eject a spent lead from said clutch member, said clutch member being bottomed adjacent the forward end of said barrel upon such release and being thereby held stationary during the separate forward movement of said propelling member, said propelling member nut portion bottoming at the forward end of said spiral feed member to terminate said separate forward movement, and said thrust washer having a plurality of radial lugs formed at the forward face thereof about said guide tube for selective lateral abutment with said propelling member nut portion lug at the rear end of said spiral feed member

60 to stop rearward movement of said propelling member therat.

7. In a mechanical pencil, a barrel, a longitudinally slotted guide tube fixed within said barrel adjacent its forward end and extending rearwardly and axially therein, a spiral feed member coaxially surrounding said guide tube within said barrel and rotatably bottomed forwardly therein, a thrust washer fixed on the rear end of said feed member, means engaged by said guide tube adjacent its rear end and held thereby in forwardly bearing relation at the rear face of said thrust washer, and a propelling member slidably disposed in said guide tube and comprising a nut portion having a lug thereon extending laterally through the longitudinal slot in said guide tube and engaging said spiral feed member for effecting longitudinal sliding movement of said propelling member within said guide tube upon rotation of said feed member, and said thrust washer having a plurality of radial lugs formed at the forward face thereof and spaced about said guide tube for selective lateral abutment with said propelling member nut portion lug adjacent the rear end of said guide tube to stop movement of said propelling member therat.

25 8. In a mechanical pencil, the structure defined in claim 7 and further characterized in that the radial lugs at the forward face of said thrust washer have the sides thereof that face in the direction in which said feed member is rotated for retraction of said propelling member formed in radial planes with respect to the axis of said feed member and the opposite sides thereof slanted from the extending edges of said first mentioned sides.

30 9. In a mechanical pencil, the structure defined in claim 7 and further characterized in that said guide tube is additionally slotted adjacent the rear end thereof opposite the longitudinal slot therein, the means engaged by said guide tube and held thereby in forwardly bearing relation at the rear face of said thrust washer comprises a pin member having a straight length disposed through the slotted rear end of said guide tube and extending at opposite sides thereof to overlie an adjacent portion of the rear face of said thrust washer, and said guide tube being inwardly crimped rearwardly of said pin member to lock it in place at the rear face of said thrust washer.

35 40 45 10. In a mechanical pencil, the structure defined in claim 9 and further characterized in that the straight length of said pin member has arcuate extensions formed at the ends thereof, and the rear face of said thrust washer is formed with a cylindrical recess in which said arcuate extensions are frictionally seated.
